UNITED STATES PATENT OFFICE.

EDGAR B. TOLMAN, JR., OF CHICAGO, ILLINOIS.

CONVEYING APPARATUS.

Application filed July 5, 1924. Serial No. 724,472.

My invention belongs to that general class of devices known as conveying apparatus, and relates particularly to an improved target and target plate construction arranged at the discharge end of the system. The invention has among its objects the production of a device of the kind described that is simple, durable, efficient and satisfactory for use wherever found applicable. More particularly it has as an object the production of a durable device of the kind described which will efficiently control the discharging of the material. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a view in elevation of my improved apparatus arranged in a storage tank shown in section.

Fig. 2 is a sectional view through the drain ring;

Fig. 3 is a sectional view through the target plate; and

Fig. 4 is a sectional view through the coupling at the juncture of the discharge pipe and fitting.

Referring to the drawings in which the preferred embodiment of the invention is shown, 1 represents a conveying system pipe which is extended as at 2, and provided with a fitting 3 at the inside of the tank, 4 being a

replaceable wearback forming a part of the fitting. 5 represents any suitable box, tank or receptacle of suitable size, shape and material, which may be provided with a cover or top 6 of suitable construction and a vent pipe

8. The tank provides a chamber 7 into which ashes or other material may be discharged and collected as necessary. The fitting is provided with a flange 9 which carries a frame 10 connected thereto by the rods 11 or

the equivalent. The frame part 10 is provided with a renewable plate 12 termed a target plate, which I generally prefer to make with ribs 13 so as to form a series of pockets 14. Material discharged from the fitting is

directed against the target plate 12, which arrests its velocity and allows it to fall into

the tank of its own weight and without packing the tank. The material generally fills up the pockets 14 in which the material solidly packs and forms substantially a target of the material discharged, which builds up as fast as it is worn away by the continual discharge against it. The construction and arrangement of the target is such that the same is in the line of the direction of travel of the material, and as the material is discharged, it tends to fill the bin substantially evenly. In other words, the material is not thrown entirely to one side or the other, nor to more or less one point from which it either must be shoveled back or reduce the capacity of the bin, but the same tends to be thrown or deflected more or less evenly about the bin.

The fitting 3 may be secured to the pipe 2 in any suitable manner, a simple construction comprising a flange 16 on the pipe 2 and a split ring 19 arranged to engage a flange 18 on the fitting, the parts being secured together by bolts 17 or equivalent means for the purpose. Generally, I prefer to provide a drain pipe 22. As shown, a drain fitting 20 is arranged between the pipes 1 and 2, the parts being secured together by bolts or their equivalent. This fitting is formed with a discharge opening 21 at the bottom, and arranged for attachment to the pipe 2 by means of a coupling 23 or equivalent means for the purpose.

It will be noted that the drain fitting 20 is slightly tapered so that the pipe 2 and fitting 3 are slightly inclined upwardly from the fitting so that any water or liquid in the line will drain back and be discharged through the pipe 22.

As before mentioned, the fitting consists of the part 3 and wearback 4. The wearback 4 is removable so that it may be removed as required for inspection or replacement. A novel connecting means for securing the wearback in place consists of lugs 25 and 26 on the parts, through which may be passed the ends of the U-bolt 27, if desired. A lug 28 may be provided on the wearback for engagement with the U-bolt 27, in which case the lugs 26 may be omitted.

The construction illustrated has many advantages. It will be noted that in the construction shown the material conveyed is discharged in an upward direction and allowed to strike at right angles against a plate, whereby it entirely loses its discharge velocity and falls freely and evenly into the tank with-

out packing, making the subsequent discharge from the tank easy. In a pneumatic or jet-conveying system the material conveyed travels at a high velocity and it is desirable to reduce this velocity after discharge which is accomplished in this construction. It will also be noted that when the system is turned off all the material will drop by gravity clear of the end of the discharge pipe. 10 This is desirable as there is no dropping back into the pipe of the material at the discharge end which might obstruct the system when it is again started in operation. The same distributes the material throughout the tank so 15 that it fills up evenly from the bottom toward the top. The parts may be easily removed for inspection or replacement. For example, the target plate 12 may be lifted out at any time for inspection and replaced or renewed, if 20 necessary, without requiring any bolting or fastening means, the weight of the same being sufficient to hold it in place. The material filling up the pockets 14 provides a face which will take the wear and which is being 25 continuously built up if any of it wears or breaks loose. The wearback 4 may be removed for inspection or replaced with ease, as may the entire fitting be disconnected from the pipe 2. Liquid and water accumulating 30 in the fitting and pocketing therein may flow back into the drain fitting 20 and thence be discharged down into and out through the pipe 22.

Having thus described my invention, it is 35 obvious that various immaterial modifications may be made in the same without departing from the spirit of my invention; hence I do not wish to be understood as limiting myself to the exact, form, construction, arrangement and combination of parts herein shown and described or uses mentioned.

What I claim as new and desire to secure 40 by Letters Patent is:

1. In a conveying apparatus of the kind described and in combination, a discharge fitting arranged with the outlet directed upwardly at an angle to the vertical and a target arranged in and transversely to the path of the material discharged from said outlet but 45 spaced therefrom.

2. In a conveying apparatus of the kind described and in combination, a conveying pipe provided with a discharge outlet and ar-

50 ranged to discharge in an upward direction at an angle to the vertical, and a target spaced from the outlet and arranged in the path of the material discharged therefrom, said target consisting of a frame and means for supporting the same on said conveying pipe, and a target plate seated in said frame. 55

3. In a conveying apparatus of the kind described and in combination, a conveying pipe provided with a discharge outlet and arranged to discharge in an upward direction, and a target spaced from the outlet and arranged in the path of the material discharged therefrom, said target consisting of a frame mounted on said conveying pipe, and a target plate seated in said frame, said target plate provided with a plurality of recesses on the impact side whereby material discharged will pack therein and provide a wear-face of the material conveyed. 60

4. In a conveying apparatus of the kind described and in combination, an inclined conveying pipe provided with a discharge outlet and arranged to discharge in an upward direction at an angle to the vertical, and a target spaced from the outlet and arranged in the path of the material discharged therefrom, said target consisting of a frame, means carried by said pipe for supporting the same, and a target plate removably seated in said frame, said target plate provided with a plurality of recesses on the impact side, whereby material discharged will pack therein and provide a wear-face of the material conveyed. 65

5. In conveying apparatus of the kind described and in combination, a receptacle, a conveying pipe projecting into the receptacle and terminating in a discharge outlet within the receptacle, said discharge outlet being directed upwardly at an angle to the vertical, and a target mounted on the conveying pipe and spaced from said discharge outlet. 70

6. In conveying apparatus of the kind described and in combination, a conveying pipe projecting into the receptacle and terminating in a discharge outlet therein, a target aligned with said discharge outlet, and means including a plurality of relatively long rods for mounting the target upon the discharge end of said pipe. 75

In testimony whereof, I have hereunto signed my name.

EDGAR B. TOLMAN, Jr.
